UNITED STATES PATENT OFFICE.

JAMES LEWIS WEST, OF OMAHA, NEBRASKA.

TELEPHONE-TRANSMITTER.

SPECIFICATION forming part of Letters Patent No. 653,721, dated July 17, 1900.

Application filed March 8, 1900. Serial No. 7,896. (No model.)

To all whom it may concern:

Be it known that I, JAMES LEWIS WEST, a citizen of the United States, residing at Omaha, in the county of Douglas and State 5 of Nebraska, have invented a new and useful Telephone-Transmitter, of which the following is a specification.

This invention relates to telephone-transmitters in general, and more particularly to 10 the class of microphone-transmitters, one object of the invention being to provide a construction of granular-carbon transmitter in which packing of the carbon will be prevented, in which the carbon may be accurately placed 15 to the proper amount, and in which there will be little or no resistance to the vibration of the diaphragm.

A further object of the invention is to provide a construction in which there will be no 20 objectionable noises produced.

Additional objects of the invention will be apparent from the following description:

In the drawings forming a portion of this specification, and in which like numerals of reference indicate similar parts in both views, 25 Figure 1 is a perspective view showing a complete transmitter constructed in accordance with the present invention. Fig. 2 is a central longitudinal section of the transmitter 30 and showing the construction and arrangement of the carbon-holding cup.

Referring now to the drawings, the transmitter of the present invention comprises a preferably disk-shaped plate 5, adapted to 35 be screwed or otherwise secured into the opening in the front of the transmitter-box, and this plate has the usual central sound-opening, to which leads the mouthpiece 6 to direct the sound-waves to the diaphragm. The dia- 40 phragm 7 is disposed against a washer 8, of paper or other suitable material, in an annular recess in the back of the plate, and in the present instance the diaphragm has a binding 9, of rubber or similar material, which 45 rests directly against the said washer. To hold the diaphragm in its place in the recess in plate 5, spring-fingers 10 are screwed at one end upon the rear face of the plate, while their opposite ends are provided with rubber 50 caps or tips 11, which bear against the binding 9. The fingers are held in place by screws to permit their ready adjustment into and out

of operative position to hold the diaphragm in place or allow its removal.

One electrode of the transmitter consists of 55 a carbon cylinder 12, which is rigidly connected with the central portion of the dia- phragm 7 through the medium of a headed bolt 13, passed through a central perforation in the cylinder and an alining perforation in 60 the diaphragm. This bolt is of conductive material and electrically connects the cylinder with the diaphragm. The opposing elec- trode is mounted upon a U-shaped plate 15, 65 the extremities of which are bent outwardly and connected to the back of the plate 5, this plate 15 being disposed diametrically of the plate 5, as shown, and with its web 17 oppo- site to the cylindrical electrode 12, so that 70 said electrode lies between the arms of the plate 15.

The electrode upon the plate 15 is in the form of a carbon cylinder 20 and is inclosed by a cylindrical metallic box 21, the electrode being held in place by a bolt 22, which is 75 passed through the electrode, then through the bottom of the box, and finally through the web of the plate 15, the nut 24 of the bolt lying against the outer face of the web of the plate and forming a means for clamping a con- 80 ducting-wire in electrical relation to the elec- trode.

The box 21 has a cap or cover 25, which is screwed onto the box, and the central por- 85 tion of the cap or cover is cut away to form an opening to receive the electrode 12. The opening in the cap is somewhat greater in diameter than the electrode, and in order to secure a close fit around the electrode and at the same time to prevent electrical con- 90 tact between the electrode and the cap a ring 27 of mica is clamped between the box and its cap, the interior diameter of the ring be- ing such as to fit closely to the electrode 12, but without retarding the movement of said 95 electrode under the influence of the vibrations of the diaphragm.

Within the box 21 and between the elec- 100 trodes is disposed a mass of granular carbon 30 in such quantity that when the electrode 12 is moved by the vibrations of the dia- phragm there will be always a path of vary- ing resistance for the flow of current between the electrodes.

Connection between the local circuit and the electrode 12 is made by means of a binding-post 35, which is mounted upon an insulating-block 36 upon the plate 15, this post 5 being in turn connected by means of a flexible wire 37 with a metallic plate 38, which is soldered to the back face of the diaphragm and near the edge of the latter. The operation of this diaphragm will be readily understood by those skilled in the art, and it will be seen that with the present structure all passing of current from one electrode to the other, excepting through the granular carbon, is prevented, while there is practically no resistance whatever to the vibration of the diaphragm, with the electrode thereon, excepting that offered by the granular carbon.

To facilitate filling of the box 21 with the proper quantity of carbon, openings 39 are 20 formed in the side of the box beyond the electrode fixed therein, and the box is provided with a lining of mica 40, which covers these openings and permits an inspection of the interior of the box without permitting escape of the carbon therefrom.

It will of course be understood that in the manufacture of the present invention any suitable materials may be used for the various parts and that any suitable proportions 30 may be observed without departing from the spirit of the invention.

What is claimed is—

1. In a telephone-transmitter, the combination with a supporting-plate having a diaphragm mounted thereon, of an electrode 35

movable with the diaphragm, a box held adjacent to the diaphragm, an electrode in the box, granular conductive material in the box and in contact with the electrodes, openings in the sides of the box having transparent 40 closures, a cap for the box having an opening in which the first electrode operates, and an insulating-ring bridging the interspace between the first electrode and the sides of the box to prevent egress of the granular conductive material.

2. In a telephone-transmitter, the combination with a supporting-plate having a diaphragm mounted thereon, of an electrode movable with the diaphragm, a plate disposed 50 diametrically of the supporting-plate, a box mounted on the last-named plate, an electrode in the box in operative relation to the first electrode, openings in the side of the box, a transparent lining for the box covering the 55 openings, a cap for the box having an opening in which the first electrode operates, an insulating-ring clamped between the box and its cap, said ring closely encircling the first electrode to prevent egress between it and the box and a filling of granular conductive material for the box.

In testimony that I claim the foregoing as my own I have hereto affixed my signature in the presence of two witnesses.

JAMES LEWIS WEST.
